[57] CLAIM

The ornamental design for a universal wheel adaptor
for alignment of wheels of a vehicle, substantially as
shown and described.

DESCRIPTION

FIG. 1 is a top plan view of a universal wheel adaptor
for alignment of wheels of a vehicle showing my new
design;

FIG. 2 is a bottom plan view thereof;

FIG. 3 is a rear elevation thereof;

FIG. 4 is a front elevation thereof;

FIG. 5 is a right side elevation thereof; and,

FIG. 6 is a left side elevation thereof.
